FIG. 1.

FIG. 2.

FIG. 3.

FIG. 4.

FIG. 1 is a top plan view of a combination toothbrush and toothbrush cleaner, showing my new design;

FIG. 2 is a side elevational view thereof;

FIG. 3 is an end elevational view thereof taken from the right of FIG. 2; and

FIG. 4 is a perspective view thereof, showing the toothbrush and toothbrush cleaner in operating position.

The dominant features of my design reside in the portions shown in full lines, portions of the brush handle being shown broken away for convenience of illustration.

I claim:

The ornamental design for a combination toothbrush and toothbrush cleaner, as shown and described.
